UNITED STATES PATENT OFFICE.

DANIEL PARKE RANSOM, OF WOODSTOCK, VERMONT.

RUG OR CARPET BEATER.

Application filed March 7, 1925. Serial No. 13,870.

This invention aims to provide an improved rug or carpet beater which is of extremely simple and durable construction, which is comparatively inexpensive to manufacture, which may be easily operated without the expenditure of laborious effort and without the application of electrical or mechanical power, and which is effective to thoroughly beat the rug or carpet to the end of expelling dirt, dust, grit, sand and other foreign matter therefrom without injuring or wearing the rug or carpet.

Other objects and advantages reside in certain novel features of the construction, arrangement and combination of parts which will be hereinafter more fully described and particularly pointed out in the appended claim, reference being had to the accompanying drawings forming a part of this specification, and in which:

Figure 1 is a fragmentary perspective view showing one embodiment of the invention.

Figure 2 is a view taken partly in front elevation and partly in section on line 2—2 of Figure 3, and

Figure 3 is a view in section on line 3—3 of Figure 2, Figure 3 also showing a section of a rug and illustrating how the beater constituting the present invention coacts therewith.

Referring to the drawings the numeral 1 designates a rotary beating element which is elongated and of polygonal and preferably octagonal form in cross section so that the periphery of the beating element presents ridges 2 and flat plane beating surfaces 3 between the ridges. The surfaces 3 provide beating means for the carpet or rug and the ridges 2 provide means causing the beating means to rise and fall whereby to engage with or to be disengaged from the carpet or rug.

The rotary beating element is provided at its ends with sockets 4 in which trunnions 5 of a wire or other suitable frame designated generally at 6 are rotatably fitted. The frame 6 has a looped attaching portion 7 fitted in a socket 8 provided in a handle 9. A ferrule 10 encases the end of the handle in which the socket 8 is formed and the ferrule is held in place by a pin 11 which also traverses the looped attaching portion 7 to hold the frame to the handle.

In use the rotary beating element 1 is applied to the reverse or underside of a carpet or rug as shown in Figure 3. In Figure 3 the carpet or rug is designated generally at A, its backing is designated at B and its pile or facing at C. As shown the rotary beating element 1 is applied to and engages the backing B of the carpet and as the beater is pushed across the backing the ridges 2 cause it to rise and fall and cause the flat beating surfaces 3 to forcibly strike the carpet and thereby beat or expel the dirt or dust therefrom. Of course the carpet A is suitably supported and stretched out flat when the beater is used. While the beater is very effective to thoroughly clean the carpet or rug, it does not wear or impair the appearance of the same since it engages the back and not the pile or facing of the carpet or rug.

I claim:

A rug or carpet beater comprising a rotary beating element of polygonal form in cross section and having a continuous unbroken periphery made up of ridges and flat beating surfaces alternating with the ridges, and means for rolling the beating element across the carpet or rug.

DANIEL PARKE RANSOM.
